(57) **CLAIM**

The ornamental design for a hanger, as shown and described.

DESCRIPTION

FIG. 1 is a perspective view of a hanger showing my new design;

FIG. 2 is a front perspective view of the hanger;

FIG. 3 is a side view of the hanger;

FIG. 4 is a bottom left angled perspective view of the hanger;

FIG. 5 is a top left angled perspective view of the hanger;

FIG. 6 is a top view of the hanger; and,

FIG. 7 is rear perspective view of the hanger.

The broken lines in FIG. 1 depict an environmental garment that forms no part of the claimed design.
